UNITED STATES PATENT OFFICE.

HIRAM GEE SEDGWICK, OF MILL VALLEY, CALIFORNIA, ASSIGNOR TO THE NATIONAL SAFETY APPLIANCE COMPANY, A CORPORATION OF CALIFORNIA.

AUTOMATIC TRAIN-STOP.

1,204,497.

Specification of Letters Patent. Patented Nov. 14, 1916.

Application filed May 26, 1909, Serial No. 498,453. Renewed November 17, 1915. Serial No. 62,077.

To all whom it may concern:

Be it known that I, HIRAM G. SEDGWICK, a citizen of the United States of America, and a resident of Mill Valley, county of Marin, State of California, have invented certain new and useful Improvements in an Automatic Train-Stop, of which the following is a full and clear specification, reference being had to the accompanying drawings, in which—

Figure 1 is a side elevation of a locomotive and a portion of a road bed provided with my invention; Fig. 2 a view partly in side elevation and partly in section showing the construction of the arm on the locomotive which coöperates with the road bed devices; Fig. 3 is an elevation of the cushioning devices for the rock shaft; Figs. 4, 5 and 6 is a series of views showing the 20 manner in which the rock shaft coöperates with the shoe on the road bed; Fig. 7 a vertical transverse section of the valve for lowering the arm carrying the rock shaft; Fig. 8 a longitudinal sectional view of the 25 outer end of the rock shaft carrying the frangible part of the electric circuit; Fig. 9 a plan view of a portion of a road bed showing one possible arrangement of the road bed device; Fig. 10 is a side elevation 30 partly in section showing a modification of the arm structure carrying the frangible wire; and Fig. 11 a view partly in section and partly in side elevation of a modified 35 form of the side arm structure, the design of this modification being to avoid the necessity of mounting a rock shaft in the arm.

This invention is designed to provide means whereby the electric circuits on the locomotive and on the road bed will be reduced to utmost simplicity and will be normally closed, whereby the danger of derangement of the apparatus is reduced to a minimum and whereby also any derangement of the apparatus will cause the brakes 45 to be applied.

The road bed appliances consist of a normally closed circuit *a* arranged in the usual or any improved manner and including a battery and a magnet *b*. In the instance 50 illustrated each circuit contains two magnets arranged one ahead of the other in the block. Each magnet is inclosed in a suitable housing *c* mounted upon a shoe *d*, said shoe being suitably mounted along side of the 55 track and having its opposite ends upturned.

The armature *e* of each magnet is pivoted on the plate *d* and carries a hook like arm *f* which when the current in the magnet is weakened falls by gravity through a slot in the plate *d* as shown in Figs. 2, 4 and 5. 60 These hooks *f* face in the direction of the on-coming train, and the idea of having two or more arranged in tandem in each block or at each danger point is to increase the degree of safety.

An arm *g* is mounted at each side of the locomotive so as to have a vertical sliding motion between the vertical bars *h* on the locomotive truck. This arm extends outwardly from the locomotive and has extending through it a hollow rock shaft *i* which carries at its inner end a depending cam *j* and at its outer end a cam *l* which normally points upwardly and is so positioned that as the locomotive passes one of 70 the shoes on the road bed this cam will strike against the upturned end thereof and rock the shaft a partial turn.

Adjacent to the cam *l* is affixed a pair of fingers *m* having extending across their 75 ends a frangible conductor *n*, whose ends are connected to the normally closed circuit *o* on the locomotive which circuit includes a brake magnet which when the circuit is opened or weakened operates a vent valve 80 or other train stopping device in any suitable manner well known.

It will be observed that the shoes on the road bed are so located with reference to the laterally projecting arm *g* on the locomotive that when the arm is at its uppermost point when the arm is raised in its frame, the cam *l* will strike the nose portion of the shoe in going in either direction.

When going forward as shown in Figs. 4 90 and 5 the cam will so strike the shoe that the frangible conductor *n* will be swung upwardly as it passes under the shoe, so that if at the time it is passing under the shoe the disrupter *f* be lowered the frangible conductor will be cut or broken at a point between its supporting fingers *m* and the brake will be applied. In going in the reverse direction, as shown in Fig. 6, the frangible conductor will be thrown or turned away 95

from the shoe and thus be out of the way of engagement with the hook *f* in case the same be set in danger position. This capacity to pass without operation in the reverse direction enables the apparatus to be duplicated 100

on opposite sides of the locomotive without the employment of reversing switches, it being simply necessary to so arrange the duplicate apparatus that they will operate ⁵versely as is evident.

Under the arm *g* is mounted a small cylinder *g* connected by a pipe *r* through a valve *s* to the usual pipe *t* running from the storage reservoir *u*. In this cylinder is a ¹⁰piston whose rod *v* bears up against the under side of the arm *g* when air pressure is let in under the piston. The object of this is to normally hold the arm in operative position (the passage through valve *s* being ¹⁵normally open as shown in Fig. 7) and yet permit the engineer in the cab to lower the arm out of operative position whenever he desires to pass a danger-set road-bed device. He does this simply by rotating the plug *w* ²⁰in valve *s* to disconnect port *x* from pipe *r* and connect exhaust port *y* to it, whereby the air under compression in cylinder *g* will escape and thus let arm *g* fall. This plug is turned by means of a depending arm *z* on ²⁵the end of the plug that is adapted to be operated by a bell crank *a'* connected to a wire *b'* extending into the cab. As this permission to pass a danger-set device can only be given to the engineer under special conditions it is desirable to make a record of each instance and for this purpose I prefer attaching the arm of a register recorder *e'* to the wire *b'*. I also prefer attaching an alarm such as a whistle *d'* to the valve *s* in ³⁰such position that when the arm is lowered the alarm will sound continuously until it is again raised to operative position.

When the locomotive is running tandem it is necessary that the control of the ⁴⁰braking apparatus be placed in the hands of the engineer on the first locomotive. To do this the usual cut off valve *e'* is employed, and in order that the arm *g* may be lowered to inoperative position when the brake apparatus is thus cut off, I provide this cut off valve with an arm *f'* and connect it by a rod or wire *g'* to bell crank *h'* arranged ⁴⁵versely to the aforesaid bell crank *a'*. When the cut off valve *e'* is operated the bell crank *h'* will swing the arm *z* in a direction opposite to the direction it is moved by the bell crank *a'*, and this action will put exhaust port *i'* in connection with pipe *r* and exhaust the same and lower the arm *g*. But ⁵⁰when the arm is lowered in this way there will be no registration of the act nor will there be any sounding of the whistle, it being unnecessary to perform these functions when the locomotive is running tandem.

⁵⁵60 I make no claim in this application for devices for thus rendering the automatic brake setting mechanism inoperative when the locomotive is running tandem. The same is covered by my copending application Serial ⁶⁵Number 763665, filed Apr. 25, 1913.

Any suitable device may be employed for resiliently holding the cam *l* in its operative position but I prefer to employ a pair of cylinders *j'* mounted upon opposite sides of the depending arm *j* and provided with suitable pistons whose rods are provided with heads *k'* bearing upon opposite sides of arm *j*. These cylinders *j'* are in constant communication by suitable pipe arrangement *l'* with the storage reservoir *u*. ⁷⁰75

The modification shown in Figs. 10 and 11 consists in doing away with the rock shaft *i* and in carrying the fingers *m* directly on the outer end of arm *g*, these arms *m* being arranged to extend upwardly so that the frangible conductor *n* will at all times lie in the path of the disrupting device *f*. In this form of device it is necessary to provide some means to protect the frangible conductor when going in the reverse direction. ⁸⁰85 This may be done in many different ways, as for instance by a cam plate *n'* pivoted between the fingers *m* at the rear of the breakable conductor *n* and held normally by a spring *o'* so as to prevent the hook *f* striking said conductor *n* when the same passes under the hook in the reverse direction, the cam *n'* simply acting to lift the hook *f* over the conductor *n* as the same passes under a hook. Of course this cam *n'* is free to swing ⁹⁰95 backwardly out of the way when the hook engages the conductor *n* in going in the opposite direction from hook *f*.

Having thus fully described my invention, what I claim as new, and desire to secure ¹⁰⁰by Letters Patent, is:

1. In a train stopping apparatus, a circuit disrupting device on the road bed, a brake appliance circuit on the locomotive normally closed, a disruptable portion of ¹⁰⁵this circuit lying in the path of the circuit disrupter on the road bed.

2. In combination with a normally closed brake appliance circuit on the locomotive, a portion of this circuit being disruptable and being extended to a point near the road bed, of an electromagnetically controlled circuit disrupter on the road bed, the circuit whereof is normally closed to hold the disrupter normally out of operative position, whereby ¹¹⁰115 but two circuits are employed and both may be normally closed.

3. In a train stopping apparatus, a circuit disrupter on the road bed and means for setting it in operative position, a normally closed brake appliance circuit on the locomotive, a portion of this circuit being disruptable and lying in the path of the circuit disrupter on the road bed, and means for shifting this portion of the circuit into and ¹²⁰125 out of the path of said circuit disrupter.

4. In a train stopping apparatus, a circuit disrupter on the road bed and means for setting it in operative position, a normally closed brake appliance circuit on the loco- ¹³⁰

- motive, a portion of this circuit being disruptable and lying in the path of the circuit disrupter on the road bed, and means for shifting this portion of the circuit into and 5 out of the path of said circuit disrupter, and means for rendering inoperative the brake apparatus simultaneously with the shifting of the circuit disrupter to inoperative position.
- 10 5. In a train stopping apparatus, a circuit disrupter on the road bed and means for setting it in operative position, a normally closed brake appliance circuit on the locomotive, a portion of this circuit being disruptable and lying in the path of the circuit disrupter on the road bed, and means for shifting this portion of the circuit into and 15 out of the path of said circuit disrupter and means for sounding an alarm continuously 20 while said disruptable part of the circuit is out of operative position.
6. In combination, circuit disrupting means on the road bed embodying a normally closed circuit, an electromagnetic and 25 a gravitating circuit disrupter, a normally closed brake circuit on the locomotive, a portion of this circuit being made frangible and arranged to pass along in the path of said disrupter, for the purpose set forth.
- 30 7. In combination with a railway vehicle carrying train stopping means, embodying a closed circuit having a disruptable part,
- of coöperating means on the road bed and consisting of a closed circuit and magnet and a gravitating disrupter adapted when 35 released to drop into the path of a disruptable portion of the aforesaid circuit.
8. An engaging arm located along the trackway, a circuit on the train, said circuit including a fragile conductor and a magnet, 40 a brake valve controlled by the magnet, said fragile conductor being adapted to engage said arm when the latter is in stop position.
9. An engaging arm on the trackway, a train controlling device, a train circuit operating the train controlling device, a fragile conductor in the circuit adapted to engage said arm. 45
10. An engaging arm on the trackway, a train controlling device, a train circuit operating the train controlling device, a fragile conductor in the circuit, said conductor being adapted to engage said arm, said arm having two positions, an engaging position assumed by gravity and a non-engaging position. 50

In testimony whereof I hereunto affix my signature in the presence of two witnesses this 25th day of May, 1909.
